Primary Examiner — Kelley Donnelly(74) *Attorney, Agent, or Firm* — Pillsbury Winthrop Shaw Pittman LLP(57) **CLAIM**

The ornamental design for an open tote tool bag, as shown and described.

DESCRIPTION

FIG. 1 is a front isometric view according to my design; FIG. 2 is a front plan view of the design of FIG. 1; FIG. 3 is a rear plan view of the design of FIG. 1; FIG. 4 is a right plan view of the design of FIG. 1; FIG. 5 is a left plan view of the design of FIG. 1; FIG. 6 is a top plan view of the design of FIG. 1; FIG. 7 is a bottom plan view of the design of FIG. 1; and, FIG. 8 is a rear isometric view according to my design. Where included, broken lines showing environment or structure are for illustrative purposes only and form no part of the claimed design. The dashed lines represent stitching and do not form a part of the claimed design.
